From the drawings and the following description, the manner and the mode of operation of which will be described, the following or substantially equivalent structure may be carried out in accordance with the principles of the invention.

UNITED STATES PATENT OFFICE

2,191,557

CONTAINER

Melvin H. Cline, Chicago, Ill., assignor to Eisenman-Kaye Company, Chicago, Ill., a corporation of Illinois

Application January 26, 1939, Serial No. 253,016

2 Claims. (Cl. 150—28)

My invention relates more particularly to containers, such as for example toilet cases, having hinged covers.

My primary object is to provide a construction of container of the character above stated, the cover of which in closed condition opposes the action of means tending to swing it to open condition, whereby when the cover is released it automatically swings to open position.

Another object is to provide a novel, simple and economical construction functioning as above stated; and other objects as will be manifest from the following description.

Referring to the accompanying drawings:

Figure 1 is a rear view in elevation of a toilet case of the type involving zipper means for holding the cover in closed condition, the case embodying my invention.

Figure 2 is an enlarged view in sectional elevation of the case of Fig. 1, the section being taken at the line 2—2 on Fig. 1 and viewed in the direction of the arrows.

Figure 3 is a plan sectional view of the case showing the zipper released and the cover in open condition, this view being taken at the line 3—3 on Fig. 4 and viewed in the direction of the arrows.

Figure 4 is a fragmentary sectional view taken at the line 4—4 on Fig. 3 and viewed in the direction of the arrows.

Figure 5 is a cross sectional view of another form of toilet case embodying my invention, the cover of the case being shown as secured in closed condition.

Figure 6 is a view like Fig. 5 and of the structure therein shown illustrating the cover in open condition.

Figure 7 is a fragmentary sectional view taken at the line 7—7 on Fig. 6 and viewed in the direction of the arrows.

Figure 8 is a plan view of still another construction of case embodying my invention, the cover, therein shown as formed of a pair of sections, being in closed condition; and

Figure 9, a fragmentary section taken at the line 9—9 on Fig. 8 and viewed in the direction of the arrows, the cover sections being shown by dotted lines in open condition.

Referring to the construction shown in Figs. 1—4, inclusive, the case therein illustrated is, as to its general features of construction, of a common type. It involves a body portion 10 shown as formed of flexible sheet material, as for example leather with a bottom plate reinforcement 11. The case also comprises a cover por-

tion 12 likewise shown as formed of flexible sheet material, as for example leather, with a plate reinforcement 13 at its top, the flexible material of the cover portion depending around its four sides and forming a skirt portion 14.

The cover portion 12 is connected along one side of the case with the body portion 10 by flexible sheet material. In the particular construction shown, by a flap 10a of flexible sheet material extending upwardly from the body portion 10 and connected with the cover portion and also by a flap 15 provided on the upper edge of the lining of the body portion and secured to the inside of the cover portion.

Closure means are provided for releasably holding the cover portion 12 in closed position on the body portion 10, these means being shown as comprising a zipper fastening means 16 as commonly provided in structures of this kind and extending from one end of the side of the body portion 10 at which the cover portion 12 is hinged thereto around the case to the other end of said side.

The upper surrounding edge of the body portion 10, at a point below the zipper 16 is provided with an endless reinforcing frame 17, preferably of stiff wire, concealed within the sheet material forming the sides of the body portion as shown.

The cover portion 12 at the edge thereof at which it is hingedly connected with the body portion 10, is reinforced by an angle shaped member represented generally at 18. The portion 19 of this member is concealed within the skirt portion 14 and extends parallel with it and at its lower edge closely adjacent the frame 17. The other portion 20 of the member 18 lies beneath the top of the cover. The member 18 is made of any desired suitably stiff material, as for example fiber board, and is shown as formed with a separate plate section 21 secured flatwise to the portion 19.

From the foregoing it will be understood that the longitudinal axis of the hinge connection between the cover portion 12 and the body portion 10 is adjacent the side of the reinforcing frame 17 at the back side of the case.

The case also comprises spring means operating when the zipper 16 is released, to cause the cover portion 12 to automatically swing to open position as shown in Figs. 3 and 4. The particular spring means shown comprise two coil springs 22 loosely surrounding the side member of the reinforcing frame 17 at the back edge of the case and each rigidly secured thereto at one end as represented at 23. The convolution of each spring 23

at its other end terminates in a substantially straight laterally projecting extension 24 which bears against the portion 19 of the reinforcement 18 and under the tension of these springs forces the cover to the open position shown, the extensions 24 of the springs being shown as located between the portions 19 and 21 of the reinforcement 18.

As will be understood from the foregoing, the swinging of the cover portion 12 to closed position so tensions the springs 22 that when the cover is released, the springs will automatically swing the cover to open position.

As will be noted, the extensions 24 of the springs shorten as the cover is swung toward closed position and lengthen as the cover is swung in the opposite direction, due to the winding and unwinding, respectively, of these extensions of the springs around the side of the reinforcing frame 17 on which they are supported. Thus these extensions of the springs cannot be rigidly fastened to the cover portion 12 without objection which is avoided in accordance with my invention by providing for relative movement between the extensions 24 of the springs and the cover portion 12. This is provided for preferably by forming guides in which the spring extensions may slide, these guides, in the particular construction shown being formed by providing cross grooves 25 between the portions 19 and 21 of the reinforcing member 20 as for example by bending the member 25 crosswise thereof at the places where these grooves are to be provided.

Referring to the construction of case shown in Figs. 5-7, this case as to its general features of construction is of a common type comprising a body portion 26 having a reinforcing frame 27, as for example of stiff wire, at its upper portion, this frame being shown as concealed within the flexible sheet material forming the side walls of the body portion.

The case also comprises a cover portion represented at 28 hinged at an edge thereof, to the back edge of the body portion 26, as by means of flexible sheet material 29 shown as in the form of a flap on the cover portion 28 and secured to the body portion 26. At the front side of the body portion 26 is a flap 30 of flexible material shown as provided with the socket portion 31 of a ball and socket fastener, the ball portion of which represented at 32 is carried by the cover portion 28, these parts serving as means for releasably securing the cover portion 28 in closed position.

The case also comprises spring means operating when the fastener device 30-32 is released, to cause the cover portion 28 to automatically swing to open position as shown in Fig. 6. The particular spring means shown comprise a coil spring 33 loosely surrounding the side member of the reinforcing frame 27 at the back edge of the case and rigidly secured thereto at one end as represented at 34. The convolution of the spring 33 at its other end terminates in a substantially straight laterally extending projection 35 which engages the cover portion 28 and under the tension of this spring forces the cover portion to the open position shown. The extension 35 of the spring is shown as located between flatwise opposed sheet-like members 36 and 37 at the interior of the cover portion 28, these members in the particular construction shown being of fairly stiff material, such as for example cardboard, to afford to the cover the desired stiffness.

As the extension 35 of the spring shortens and lengthens as the cover is swung to closed and open position, respectively, provision is made for relative movement between the cover portion 28 and the extension 35, by forming a groove 38 between the sheet members 36 and 37 in which the extension 35 is slidably guided.

The case is shown as provided with a check strap 39 connected at its opposite ends with the body portion 26 and the cover portion 28 to positively prevent the swinging of the cover beyond a certain position under the action of the spring.

In Figs. 8 and 9 I have shown my invention as applied to a case having a body portion 40 such as that shown in Figs. 5-7, with a cover portion formed of two separate sections 41 hinged to opposite edges of the body portion 40 as for example as explained of the construction shown in Figs. 5-7, their inner edges substantially meeting, at which edges they are shown as equipped with means holding them in closed position shown as in the form of a zipper 42.

The cover sections 41 are thus adapted to be swung upwardly and outwardly, to the dotted line positions shown in Fig. 9, to open the case.

In this construction the body portion 40 is provided with a reinforcing frame 43 at its upper edge and corresponding with the reinforcing frame 27, and each of the cover sections 41 is provided with spring means for automatically swinging it to open position when the zipper 42 is released. The spring means shown are the same as those provided in the construction of Figs. 5-7, but in this particular construction two springs, represented at 44, for each cover section 35 and having lateral substantially straight extensions 45 are provided, whereas only one spring is shown for the single cover section of Figs. 5-7.

It will be understood that the matter of the number of the springs employed is of no particular moment. In the constructions shown in Figs. 1-4 and 8 and 9 two springs are employed for each swinging member, whereas in the construction shown in Figs. 5-7 but one spring is shown, but it will be understood that if desired a single spring may be used in place of the double springs of the first two referred to constructions, and two springs may be used instead of the single spring of the other construction; or if desired, more than two springs may be employed for each swinging member.

While I have illustrated and described certain particular constructions constituting embodiments of my invention, I do not wish to be understood as intending to limit the invention thereto as the structures shown may be variously modified and altered and the invention embodied in other forms of structure without departing from the spirit of the invention.

What I claim as new and desire to secure by Letters Patent, is:

1. A container comprising, in combination: a body portion comprising a flexible side member and a rigid bottom member secured to one edge of said side member; a rigid, continuous, wire frame carried in a pocket at the open edge of said side member; a coiled spring surrounding and secured at one end to the wire of said frame; a cover member hinged to said body member and formed with a rigid portion; the remaining end of said coiled spring extending to uncoiled position and held in sliding engagement with said rigid portion; said spring placed in coiling compression by closure of said cover about its hinge; external and internal portions of the side mem- 75

ber extending and secured to said cover member to form portions of the hinge; and means to hold the cover closed against action of said spring tending to open the same.

5 2. A container comprising, in combination: a body portion comprising a flexible side member and a rigid bottom member secured to one edge of said side member; a rigid, continuous, wire frame carried in a pocket at the open edge of said side member; a coiled spring surrounding and secured at one end to the wire of said frame; a cover member hinged to said body member and formed with a rigid portion extending parallel

with said rigid bottom member and with a flange extending normal thereto to reinforce the hinged portion; the remaining end of said coiled spring extending to uncoiled position and held in sliding engagement with said rigid cover flange; said spring placed in coiling compression by closure of said cover about its hinge; external and internal portions of the side member extending and secured to said cover member to form portions of the hinge; and means to hold the cover closed against action of said spring tending to open the same.

10 MELVIN H. CLINE.
